SIGNALING SYSTEM

Max Geiger, Berlin, Germany, assignor to Tele-funken Gesellschaft für Drahtlose Telegraphie m. b. H., Berlin, Germany, a corporation of Germany

Application February 20, 1937, Serial No. 126,783
In Germany February 25, 1936

6 Claims. (Cl. 178—69.5)

This invention relates to signaling systems, and in particular, interlaced scanning systems such as used in television, for example, it is accordingly the purpose of this invention to provide a new method and means for producing improved interlaced scanning in television signaling systems.

Turning to the drawings, in which Figs. 1 through 6 show graphically the array of line and framing synchronizing impulse sequences useful to explain the operation of my invention; and

Fig. 7 shows in block diagram form the apparatus for producing the interlaced synchronizing system embodied in my invention; I will describe the invention in more detail below.

For the transmission of television pictures it has been suggested in the prior art to use an interlaced or skip-line method in such a way that each line series or sequence (or partial scan) would consist of a fractional number of frame or picture lines, so that the complete picture to be televised would be entirely transmitted only by a plurality of such line sequences or partial scans. The time-base of the line impulses (horizontal impulses) and the line-sequence impulses (vertical impulses) is shown in Fig. 1 for the simple instance where the entire frame or picture is to comprise merely 21 lines or strips, and where the whole frame is to be transmitted by merely two partial scans of line-sequences. In the said figure, the horizontal impulses are designated by H and the line-sequence impulses by V. Each of the line sequences has the same periodicity of $10\frac{1}{2}$ line lengths. The fact that in this method quantity d , that is, the time interval between a line sequence impulse V and the respective preceding line impulse H differs for each line sequence constitutes a serious drawback for the reason that customary practice is to transmit the impulses H and V with like amplitude, and that the impulses V must be separated from the impulses H by the aid of frequency selector or filters. Now, the said frequency filter means, upon the first line sequence or partial scan for which quantity d is always equal to a full-line length is in a state different from that in the next partial scan or line sequence for which quantity d amounts to only $\frac{1}{2}$ a line. The result is that, even if the line sequence impulses V are perfectly equal to one another, the frequency selector means will react or respond dissimilarly in both instances, with the consequence that the lines of one sequence or partial scan will not come to fall exactly into the spaces or intervals of the respective other

partial scan, and this is extremely annoying when viewing the incoming picture. In order to more clearly understand what follows, it must also be noted that quantity D which stands for the time interval between the beginning of a line-sequence impulse and the first line impulse of the next line sequence or partial scan differs in size for each line sequence in the before-mentioned method. To summarize, the values of d and of D are of dissimilar values for each partial scan.

In order to obviate the difficulties due to such difference in operation of the frequency selector filter means which is caused by the variability of quantity d , an interlaced-scanning method has been suggested in the earlier art in which quantity d for each line sequence is equally great, while quantity D for each line sequence is also of the same value (see co-pending application Ser. No. 124,977, for a "Saw-tooth generator", filed Feb. 10, 1937, by Robert Andrieu). The time representation of the shape of the line impulses H and the sequence impulses V for this last-named method according to Fig. 1 is illustrated in Fig. 2. The two line sequences contain dissimilar numbers of line lengths, i. e., 11 and 10 lines, assuming again a television frame comprising 21 lines only. Quantity d in this instance is the same for each line sequence, and accordingly the frequency selection difficulties are absent in this method. Also quantity D is the same for each partial scan. But the first line sequence or partial scan of each frame, contradistinct to the method illustrated in Fig. 1, is no longer of the same duration as in the second partial scan. However, in practicing this method it is necessary at the receiving end that the saw-tooth generator for the vertical deflection should be so designed that upon each sequence impulse it should return the same amount, regardless of the number of lines contained in the previous partial scan or line sequence. The initial position of the cathode-ray pencil building up and delineating the incoming picture, as will thus be noted, is not the same for each partial scan inasmuch as the duration of the various line sequences is different, and since the distance which the pencil is to skip back after completion of each partial scan must in each instance be the same as indicated. Now, a saw-tooth generator which in one impulse, regardless of the state of deflection of the cathode-ray pencil prevailing at a given time will always return the same distance, is not quite so simple in its construction as the usual sawtooth oscil-

lators usable in connection with the method indicated in Fig. 1. For instance, for the method Fig. 2 it is not possible to use the circuit organization most commonly used in present day practice in which a condenser is charged up by way of a resistance from a D. C. source of supply, while upon the arrival of the sequence impulse a thyratron connected in parallel relation to the condenser is ignited. It will be remembered that the discharge of a thyratron is caused to discontinue only when the condenser has been discharged to the same fixed voltage. On the contrary, in the method covered by Fig. 2 a circuit scheme must be used in which the condenser, independently of the potential to which it has been charged up in the course of a partial scan will in each case yield the same quantity of electricity. This condition may be satisfied, for example, by the aid of a high-vacuum tube connected in what is known as the blocking-oscillator circuit organization. What is meant by this is a regenerative tube in which the coupling between the plate and the grid circuits is made extremely close, and in which, upon the arrival 25 of an impulse at the grid, a brief, but powerful current is caused to flow in the plate circuit which reduces the grid potential to a value away below the lower bend of the grid-plate (mutual) characteristic whence the grid potential will rise again in a gradual way until the time of incipient flow of plate current which is initiated by the next impulse. Hence, what is a typical fact for the interlaced-scan method according to Fig. 2 is that the values of d and D for each 30 partial scan or line sequence are alike.

Now, according to the present invention the values of d for each line sequence or partial scan are to be made of like size, while the values of D are to be made dissimilar. On the one hand, 35 this eliminates such difficulties as have been encountered in connection with frequency filtering as explained by reference to Fig. 1, while, on the other hand, there is a chance to work again with a standard type of saw-tooth generator, which, at the beginning of each partial scan or line sequence may be in the same state. In other words, when working in accordance with the present invention, the condenser of the vertical saw-tooth oscillator can again be discharged across a thyatron tube.

Fig. 3 shows the impulse sequence. It will become clear therefrom that the line sequence impulse, in each partial scan, presents the same distance from the preceding line-sequence impulse, with the result that difficulties previously attendant upon filtering are precluded. Moreover, the time interval between the initiation of a line-sequence impulse and the following line impulse differs for each partial scan of the frame. 45 The line sequences, just as in the method indicated in Fig. 2, though contradistinct to the method covered by Fig. 1, comprise a different number of line lengths, namely, $10\frac{1}{2}$ and 11 lines. But the number of lines per frame, contradistinct to the methods according to Figs. 1 and 2, is a fractional number.

By reference to Figs. 4 and 5 there shall first be explained the building up of a frame or picture. In the case of Fig. 4, the horizontal co-ordinate 50 stands for the time, and the vertical co-ordinate for the vertical direction in the television frame. The times between the incipient line-sequence impulse and the beginning of the vertical deflection for the next partial scan is here assumed to be 55 equal to two line lengths. At the instant t_1 when

a partial-scan impulse starts, the saw-tooth oscillator begins to run back so that at instant t_2 it has been restored to its initial state. Then the vertical deflection starts in the course of which lines 1 to 7 of the first line sequence are delineated (traced). A distance equal to one line length from the seventh line impulse, that is to say, at instant t_3 , another partial-scan impulse starts, and at time t_4 which again is two lines away from time t_3 , the vertical deflection for the second partial scan commences. The line impulses of the said second sequence occur at such instants that the lines of the second partial scan come to lie between the lines making up the first line sequence. Again seven lines are delineated, and these, as stated, fill up the spaces left by the first partial scan. At instant t_5 , following the seventh line impulse of the second partial scan, there is provided again a new sequence impulse, spaced one line apart, which initiates a new line sequence whose lines come to coincide or register with those of the first-mentioned line sequence or partial scan (between t_2 and t_3). 10

In Fig. 5 the lines of the partial scan occurring between times t_2 and t_3 are indicated solid, while 15 the lines between t_4 and t_5 are represented dotted.

The method here disclosed, like the methods according to Figs. 1 and 2, is useful not only in the case of two partial scans per frame but also in cases where the partial scans or subdivisions of a frame amount to three, four or more interlacings. 20 In the general instance where n many line sequences or partial scans exist per picture, there holds then true:

35

d constant

$$D = p, p+1/n, p+2/n \dots p+\frac{n-1}{n}$$

where d and p may be of any desired size. In the 40 method covered by Fig. 3, $d=1$ and $p=3\frac{1}{2}$.

Before the production of the impulse sequences in a method according to this invention, is discussed by reference to Figs. 6 and 7, the fact is to be emphasized that in the new method here disclosed, as follows from Fig. 3 any two line impulses, inside the first frame, present an integral time distance measured in terms of line lengths, whereas the distance between any desired line impulse of the frame and any random line impulse of the second one is not an integer. Applied to the general case where $d=\text{constant}$ and $D=p+1/n, p+2/n$, etc. the said rule reads as follows: Inside the first picture, any two line impulses present a distance between each other (expressed in terms of line lengths) which, when divided by the line length, leaves a different remainder than the time interval between any given impulse of the first frame and any desired impulse of at least one of the following $n-1$ pictures. On the other hand, for the time interval between two random impulses of the first and at least one of the following $n-1$ pictures there holds true what has been pointed out above by reference to Fig. 3 in regard to the interval between two impulses of the first and of the second frame. 55

Fig. 6 again covers the simple instance where there are only two partial scans per frame, with $21\frac{1}{2}$ lines per frame. The basis is an impulse 60 chain or sequence I which contains impulses of a frequency twice the line frequency. From this sequence of impulses, by means of frequency division, here are made the two impulse chains II and III which are in phase opposition, though 65

having the same frequency. Such phase opposition may be insured for instance, in a simple manner by the aid of a push-pull scheme in the output stage of the frequency divider. From the impulse series I are further made two chains IV and VI whose impulses are of a frequency twice that of the impulses contained in sequence I, though presenting a phase angle equal to the period of I. If, then, by the aid of the impulses of sequence II the impulses in sequence VI are "keyed" (in other words, if impulses VI are allowed to become operative when an impulse of sequence II exists, while suppressing them during the intervals between the impulses of sequence II), it is possible to obtain the line impulses for the first frame. The line impulses for the second frame are produced in the same manner by keying sequence IV by the aid of sequence III. The total impulse series which is made up of sequence or chain VII is obtained if to the line impulses ensuing in a way as indicated from IV and VI, vertical impulses are added, say, in a fashion described in the co-pending patent application Ser. No. 124,977, referred to above.

25 A schematic representation of the circuit organization required to produce the impulse mixture is shown in Fig. 7. 20 denotes the impulse generator for sequence I. It feeds a frequency divider 21 with a push-pull output stage 30 which by way of wires 22 and 23 furnishes the impulse series II and III. 24 and 25 denote two impulse generators which may consist of multi-vibrators having a frequency half the natural frequency of chain I, the said impulse generators 35 being designed to be connected and disconnected by way of the leads 26, 27, that is, impulse chains IV and VI. In a suitable device, say, a mixer hexode 28, there is brought about the combination of the line impulses for the first and 40 for the second frame, and on the line 29 there arises the horizontal impulse mixture or spectrum so that the lead 31 will deliver the impulse chain VII.

The impulse generator 20, for example, may 45 take the form shown in Fig. 2 of U. S. Patent No. 1,802,745, issued April 28, 1931, to James N. Whitaker for "Dot multiplex" and the multi-vibrators 24 and 25 may be of the form described in the paper entitled "A convenient method for 50 referring secondary frequency standards to a standard time interval" by Hull and Clapp in the Proceedings of the Institute of Radio Engineers, for February 1929, beginning at page 252 et seq. and in particular, at page 258, or in the 55 paper entitled "Universal frequency of standardization from a single frequency standard" by J. K. Clapp, which appeared in the Journal of the Optical Society of America, volume 15, 1927, at page 25.

Having described my invention, what I claim is:

1. A synchronizing system comprising an impulse generator, a push-pull amplifier, means to feed energy from the impulse generator to the push-pull amplifier, a plurality of multi-vibrators, means to feed energy from both the impulse generator and the push-pull amplifier to each of the plurality of multi-vibrators, and means to derive energy from each of the multi-vibrators and means to combine the derived 10 energies.

2. A synchronizing system comprising an impulse generator, a push-pull amplifier, means to feed energy from the impulse generator to the push-pull amplifier, a plurality of multi-vibrators, means to feed energy from both the impulse generator and the push-pull amplifier to each of the plurality of multi-vibrators, means to derive energy from each of the multi-vibrators, means to combine the derived energies, 15 20 and means to transmit the combined energies.

3. A synchronizing system comprising an impulse generator, a push-pull amplifier, means to feed energy from the impulse generator to the push-pull amplifier, a plurality of multi-vibrators, means to feed energy from both the impulse generator and the push-pull amplifier to each of the plurality of multi-vibrators, means to derive energy from each of the multi-vibrators, means to combine the derived energies, 25 30 means to transmit the combined energies, means to combine the combined energies with picture signals, and means to transmit the combined last-named combined energies.

4. The method of interlacing in a television system which comprises scanning a portion of a picture area over a predetermined number of integer line paths, and scanning the remainder of said picture area over a non-integer number of line paths, said first and second named paths 35 alternating with each other.

5. The method of interlacing in a television system which comprises scanning a portion of a picture area over a predetermined number of integer line paths, and scanning the remainder of said picture area over a number of paths differing from said predetermined number of paths 45 by a fractional amount of one path, said first and second named paths alternating with each other.

6. The method of interlacing in a television system which comprises scanning a portion of a picture area over a predetermined number of integer line paths, and scanning the remainder of said picture area over a number of paths differing from said predetermined number of paths 55 by one-half, said first and second named paths alternating with each other.

MAX GEIGER.
